US00D590765S

(12) **United States Design Patent**
Matsumoto

(10) **Patent No.:** **US D590,765 S**
(45) **Date of Patent:** **** Apr. 21, 2009**

(54) **AUTOMOBILE TIRE**

(75) Inventor: **Hiroyuki Matsumoto**, Osaka (JP)

(73) Assignee: **Toyo Tire & Rubber Co., Ltd.**,
Osaka-shi (JP)

(**) Term: **14 Years**

(21) Appl. No.: **29/268,282**

(22) Filed: **Nov. 2, 2006**

(30) **Foreign Application Priority Data**

Jul. 7, 2006 (JP) 2006-20763

(51) **LOC (9) Cl.** **12-16**

(52) **U.S. Cl.** **D12/519**

(58) **Field of Classification Search** D12/501,
D12/505-532; 152/209.1, 209.8, 209.9
See application file for complete search history.
